UNITED STATES PATENT OFFICE

PAUL B. RENFREW, OF FORT WAYNE, INDIANA, ASSIGNOR TO S. F. BOWSER & COMPANY, INC., OF FORT WAYNE, INDIANA, A CORPORATION OF INDIANA

OUTLET VALVE FOR OIL DISPENSERS

Application filed September 15, 1927. Serial No. 219,671.

My invention relates in general to oil dispensers of that type known to the trade as oil fountains and recently adopted as a means of selectively dispensing various grades of lubricating oils at automobile service stations.

The present case is more particularly concerned with an outlet valve for these dispensers which has for its primary object the provision of a valve which will serve in the capacity indicated to the best possible advantage taking into account positive operation without leakage, a quick cut-off, and other desirable features which are necessary in a valve of this kind.

Further objects and features of the invention are exemplified in the combination and arrangement of parts shown in the accompanying drawings and described in the following specification, and are more particularly pointed out in the appended claims.

In said drawings:

Fig. 1 is a view in side elevation and partly in section of the distributing head of an oil dispenser and illustrating the application of my improved valve;

Fig. 2 is a view in vertical section of my improved valve;

Fig. 3 is a view in horizontal section of my improved valve;

Fig. 4 is a view in vertical section of the valve taken from a different side than the section in Fig. 2;

Fig. 5 is another horizontal section of the valve taken at a higher elevation than that of the section in Fig. 3;

Fig. 6 is a top plan view of the distributing head of the dispenser; and

Fig. 7 is a sectional view taken on the line 7-7 of Fig. 6 and looking in the direction of the arrows.

Since the valve has been designed primarily for the particular use described, its application to an oil dispenser of the character described is illustrated in the drawings. The dispenser, in this connection, or at least that part of the assembly thereof with which the valve is associated, comprises, for the most part, a cylindrical pipe housing 5, the upper end of which is seated in an anti-

recess 6 on the periphery of the downwardly depending central boss 7 of the distributing head 8. The head 8 is made preferably as a casting with a central bore 9. Branching outwardly at an angle to one another from this central bore 9 are a plurality of distributing channels 10, the intake ends of which are grouped around the central bore 9 and have threaded connections 11 for the threaded ends of a series of supply pipes 12 which extend up through the housing 5. The opposite ends of the distributing channels 10 are made with flanged terminations 13 having internal annular recesses 14 providing seats for the glass cylinders 15. These cylinders are intended to contain the oil as it is supplied through the pipes 12, one pipe being provided for each cylinder so that as many different grades of oil may be displayed through the cluster of cylinders as there are cylinders to accommodate the same. The opposite end of each of the oil cylinders 15 is received in the packed annular recess 16 of the valve housing 17 and to suspend the oil housings 17 with the glass cylinders 15 confined between them and the distributing head 8, a rod 18 is provided for each cylinder. These rods pass up through the cylinders with their upper ends extending through the bores 19 in bosses 20 on top of the head 8 with cap nuts 21 engaging the threaded ends of the rods and bearing upon suitable gaskets 22 which rest upon the bearing surface of the bosses 20 around the bores 19. The opposite ends of these rods 18 are threaded into sleeves 23 which are centrally located in the top of the valve housing 17. A drain cock 24 may be provided for each of the distributing channels 10 with the plugs thereof threaded into the openings 25 of the channels from the sides thereof, just above the cylinders 15.

A dome-like cover 26 may be provided for the assembly of the distributing head, the same being supported by the walls 27 which make up the squared enclosure on top of the head 8. The webs between the distributing channels 10 of the head 8 are provided with an opening 28 between each pair of the distributing channels for suspending the light sockets 29, with the light bulbs 30 there-

of thus positioned to illuminate the oil cylinders 15 to make an effective display of oil contained therein. The cords for the lights may be distributed with respect to the openings 28 from the conduit pipe extending up through the pipe housing 5 and fitted into the central bore 9 of the head 8. One of the light cords may lead to a light socket 31 which is threaded into the top part 32 of the dome 26.

Referring now to the detail construction of the valves which are mounted to the ends of the oil cylinders 15, attention is directed particularly to Figs. 2 to 5, inclusive.

15 Since all of the valves are identical in their construction and combination of parts, only one of the same will be specifically referred to.

The housing 17 is preferably produced as a casting having a lower threaded end 33 20 for the reception of the cap closure 34, the same having a central bore 35 which serves as an outlet for the oil. The construction of the cap 34 includes an annular countersink or recess 36 for holding a packing 37 which 25 serves as a soft, resilient seat for the circular rib 38 on the bottom of the valve 39 and as a gasket for the cap closure 34. The valve is further provided on its bottom with a central plug or plunger 40 which is positioned 30 co-axially with respect to the outlet bore 35 which it occupies when the valve is closed. The plug will serve to dispose of the oil in the bore 35 as the rib 38 comes to rest on its seat 37. The valve 39, as is best illustrated 35 in the horizontal sections 3 and 5, is made with diametrically opposed radial projections or ribs 41. These ribs extend from the top of the valve flush with the bottom thereof, terminating above the rib 38. The 40 sides of the ribs 41 have a ground fit with the cylindrical interior wall of the housing 17 but the fit is sufficiently free to permit the valve to be moved up and down within the housing. One of these ribs, namely 42, is 45 much thicker than the other three and is arranged opposite the space 43 which communicates with the interior of the valve housing and is formed in a projection 44 on one side of the housing. The space 43 serves to 50 accommodate a pinion 45 which is positioned to mesh with the rack teeth 46 on the face of the projecting rib 42. The pinion 45 is fixed upon a shaft 47. One end of this shaft in advance of the pinion 45 is journaled 55 as at 48 in a bearing provided in the projecting side 44 of the valve housing.

The shaft is provided with a ring 49 which is made to fit the circular reduced diameter of the opening between the shaft housing 60 50 and the space 43. This ring serves as one barrier to prevent leakage of oil through the shaft housing and also as a centering bearing for the shaft. The stuffing box in the shaft housing is provided by internally 65 threading the end of the shaft housing for

the reception of the packing gland 51 which wedges the packing of the stuffing box around the shaft and against the beveled end of the housing just in front of the ring 49. A lock nut 52 may be threaded on the gland 70 51 to hold an adjustment thereof.

The rotation of the shaft 47 is effected by the winged handle 53, the collar 54 thereof being slipped over the end of the shaft housing 50 as a cap and having a central opening through which the threaded end 55 of the shaft extends. A washer 56 and nut 57 holds the cap on the shaft.

The valve 39 is made with an opening 58 co-axially disposed relatively of the plunger 40 for the coiled spring 59. The upper coils of this spring are wound around the end of the rod 18 and bear against the under side of the sleeve 23 so as to impart a downward thrust to the valve and hold it seated under tension.

When it is desired to draw a quantity of oil, a suitable measure is placed below the valve which controls the outlet of oil from the cylinder containing the grade of oil desired and the handle 53 is then turned to the left, as an example. This rotates the shaft 47 and the pinion 45. The pinion being in constant mesh with the rack face 46 on the rib 42 will elevate the valve 39 against the resistance of the spring 59, raising the rib 38 off its seat and withdrawing the plug or plunger 40 out of the bore 35. The oil is supplied to the cylinders 15 under pressure and they are maintained full at all times. Since there is no obstruction between the cylinders and the lower part of the valves, the oil feeds down the open spaces around the valves, between the ribs 41 and the rib 42 into the flared area over the packing 37 where it is obstructed by the rib 38 acting as a seal. When the valve is raised, the rib 38 is raised off its seat upon the packing and the plunger 40 is raised out of the outlet bore, as stated, which leaves an unobstructed outlet for the oil through the bore into the measure.

The cut-off is effected by turning the handle in the opposite direction which closes the valve with the aid of the spring 59.

As indicated by the dotted lines in Fig. 4, the outer walls of the valve 39 between the radial ribs 41 and 42 are slightly slanted from top to bottom whereas the faces of the ribs are perpendicular.

The cap closures 34 for the valves are knurled, as best shown in Fig. 1. This provides a roughened hand grip by which the caps may be screwed on the valve housings so as to jam the packing 37 tightly up against the edge of the housings to make a leak-proof connection.

Obviously those skilled in the art may make various changes in the details and arrangement of parts without departing from the spirit and scope of the invention as de-

fined by the appended claims, and I wish therefore not to be restricted to the precise construction herein disclosed.

I claim:

5. 1. In a valve assembly, a housing having a cap for closing one end thereof provided with an outlet, a valve seat surrounding said outlet, a valve in the housing adapted to occupy said seat with a plunger on the bottom of the valve adapted to occupy said outlet, said valve having spaced radial ribs providing spaces between the valve and housing extending to the bottom of said valve, and means on the outside of the housing for raising the valve relatively of said seat. 70
10. 2. In a valve assembly, a housing having a cap for closing one end thereof provided with an outlet, a valve seat surrounding said outlet, a valve in the housing adapted to occupy said seat with a plunger on the bottom of the valve adapted to occupy said outlet, said valve having spaced radial ribs providing spaces between the valve and housing extending to the bottom of said valve, and means on the outside of the housing for raising the valve relatively of said seat, comprising a handle, a shaft on the handle extending into the housing, a pinion on the shaft, and a rack on one of said radial ribs 80 with which said pinion meshes. 85
15. 3. A valve assembly comprising a housing, a cap for one end of the housing having an outlet therein, a valve within the housing for opening and closing said outlet and having a plunger thereon for entering the outlet and forcing liquid therethrough, and a gasket for said cap surrounding said outlet and providing a seat for said valve, said valve having a circular rib for contact with said gasket, and said outlet being disposed within the boundary of said rib. 90
20. 4. A valve assembly comprising a housing having an inlet and an outlet, a valve seat adjacent the bottom of said housing surrounding said outlet, a manually operable valve for said seat, said valve having a plurality of spaced radial ribs in wiping contact with the inner wall of said housing to provide passageways for the flow of liquid from said inlet to said outlet, and an annular rib on the bottom of said valve within the radius of said ribs, a plug on the bottom of the valve surrounded by said annular rib and normally seated in said outlet, and means comprising rack and pinion mechanism associated with said valve for lifting and lowering said annular rib relatively to said seat and also lifting and lowering said plug to control the opening and closing of said outlet. 105
25. 5. A valve assembly of the class described comprising a housing having an inlet and an outlet, a valve seat adjacent the bottom of said housing surrounding said outlet, a valve for said seat comprising an annular rib on the bottom of the valve, spaced-apart longitudinal ribs on said valve in wiping contact with the inner wall of said housing and providing passageways for the flow of liquid from said inlet to said outlet, a plug on the bottom of said valve surrounded by said annular rib and seated in said outlet, and manually operated means for operating said valve to lift and lower said annular rib relatively to said valve seat and also lifting and lowering said plug to control said outlet. 115
30. 6. In a valve assembly, the combination with a housing having an inlet and an outlet, of a valve in said housing provided with longitudinal spaced-apart ribs engaging the inner wall of said housing to guide the valve in its movements and to provide passageways for the flow of liquid from said inlet to said outlet, a valve seat around the outlet, an annular rib on the bottom of the valve within the radius of said longitudinal ribs, said annular rib being adapted to occupy said valve seat, a plunger within the radius of said annular rib adapted to occupy said outlet when the valve is seated, a rack on one of said longitudinal ribs, a pinion meshing with said rack, and actuating means extending exteriorly of the housing for raising and lowering the valve by operating said rack and pinion. 120
35. 7. A valve assembly comprising a housing, a cap connected to one end of said housing and having an outlet opening therein, a valve seat clamped by said cap to said housing and surrounding said outlet opening, a valve in said housing adapted to occupy said valve seat when in closed position, and a plunger extending from said valve and adapted to occupy said opening when the valve is closed. 125
40. 8. A valve assembly comprising a housing, a cap connected to one end of said housing and having an outlet opening therein, an annular gasket clamped by said cap to said housing and surrounding said opening to serve as a valve seat, and a valve in said housing adapted to occupy said valve seat when in closed position. 130
45. 9. A valve assembly comprising a housing, a cap adapted to be secured to one end thereof, said cap having an outlet opening, an annular gasket adapted to be clamped by said cap to said housing and surrounding said opening to serve as a valve seat, a valve in said housing adapted to occupy said valve seat when in closed position, and a plunger extending from said valve adapted to occupy said opening when said valve is closed. 135
50. 10. A valve assembly comprising a housing having a lower open end, a removable cap screw-threaded onto such lower end of the housing, said cap being provided with a central opening therein, a gasket between said cap and the lower end of said housing adapted to be clamped by said cap to said housing, said gasket extending radially in. 140

ward toward said central opening in position to serve as a valve seat, and a valve in said housing adapted to occupy such valve seat when in closed position.

5 11. A valve assembly comprising a housing, a cap for one end of said housing having an outlet therein, an annular gasket surrounding said outlet and clamped by said cap to said housing, a valve adapted to be seated against that portion of said gasket between the housing and said opening when the valve is closed, and a plunger extending from said valve and adapted to occupy said opening to force liquid therethrough when 10 the valve is being closed.

15 12. A valve assembly comprising a housing, a cap secured thereto and having a discharge outlet extending therethrough, an annular gasket in an annular seat surrounding 20 said outlet and adapted to be clamped by said cap to said housing with an annular portion of the gasket between the housing and the said outlet serving as a valve seat, and a valve in said housing adapted to occupy said valve 25 seat in closed position.

13. A valve assembly comprising a housing, a cap having an outlet opening extending therethrough, a gasket adapted to be clamped by said cap to said housing and having 30 an inwardly extending portion to serve as a valve seat, and a valve within said housing having an annular rib adapted to occupy said valve seat when the valve is in closed position.

35 14. A valve assembly comprising a housing, a cap for closing one end thereof, said cap having an outlet opening extending therethrough, a gasket adapted to be clamped by said cap to said housing and having an 40 inwardly extending portion to serve as a valve seat, a valve having an annular rib adapted to be seated on said gasket when the valve is closed, and a plunger extending from said valve in position to occupy said 45 opening when the valve is closed.

15. A valve assembly comprising a housing, a cap for closing one end thereof, said cap having an outlet opening extending therethrough, an annular gasket surrounding 50 said opening and clamped by said cap to said housing, a valve having longitudinal spaced-apart ribs to provide passageways for the flow of liquid through said housing to said opening in said cap, means for operating said valve from the exterior thereof, said valve being adapted to occupy a portion of said gasket as a seat when in closed position, and a plunger extending from said valve through said opening when the valve is being closed to force liquid from said opening.

In testimony whereof I have signed my name to this specification on this 1st day of Sept., A. D. 1927.

PAUL B. RENFREW.
